UNITED STATES PATENT OFFICE.

GEDOR W. ALDEEN, OF ROCKFORD, ILLINOIS, ASSIGNOR TO FYRAC MANUFACTURING CO., OF ROCKFORD, ILLINOIS, A CORPORATION OF ILLINOIS.

TIMER.

Application filed April 19, 1923. Serial No. 633,076.

This invention relates to timers or commutators for internal combustion engines.

One of the primary objects is to provide in a timer, an all-metal track for the rotating contact or brush, which track is preferably carried by an insulating block and includes a series of contacts or terminals connected by conductors to the ignition means in the cylinders of the motors. Another object in this regard, is to so construct said track and revolving contact that the latter will have continuous bearing on the track. This construction insures even wear and relatively long life for parts of this character. Furthermore, in the event that the fixed contacts should require cleaning, the block on which they are carried may be removed and the entire track refinished on a flat abrasive surface.

Another object is to provide in a timer an all-metal track of the character described comprising segmental elements, including the terminal contacts, the initial contact faces of which are disposed in radial planes, and in the provision of a revolving brush, the initial contact face of which is likewise disposed in a radial plane, so that such edge will make simultaneous contact from end to end with the respective initial contact faces of said terminal contacts. This construction prevents uneven wear and arcing and is a factor in producing superior ignition qualities.

Still another object is to provide a timer of generally improved construction comprising three principal units, namely, a shell which houses the rotating brush, an insulating block which carries the terminal contacts and binding posts for the conductors, and a cover which incloses and protects the binding posts and conductor connections. These units seated one upon another are held in operative relation by fastening means permitting quick detachment or removal of the units without the use of tools or without removing any fastening parts. Thus, the cover may be quickly removed for access to the conductor wires or their connections to the binding posts. The insulating block may be removed for inspection of or cleaning of the contact faces and the shell may be removed from its position about the brush. In the preferred form of my invention the fastening means referred to are in the form of spring clips carried by the shell

and engaging the insulating block and cover respectively so that each is held in operative position by independent spring elements.

My invention also contemplates the provision of a timer of the character described, composed of such few parts and constructed in such simple manner as to enable production at a comparatively low cost and which at the same time will be thoroughly practical and durable.

Other objects and attendant advantages will be appreciated by those skilled in this art as the invention becomes better understood by reference to the following description when considered in connection with the accompanying drawing, in which—

Fig. 1 is a front view of a timer embodying my invention;

Fig. 2 is a front view with the cover removed;

Fig. 3 is a vertical section taken substantially on the line 3—3 of Fig. 2;

Fig. 4 is a rear view of the timer;

Fig. 5 is a view of a detail which will be described later;

Fig. 6 is a side view showing the spring snap fasteners for holding the insulating block and cover in position;

Fig. 7 is a fragmentary section taken substantially on the line 7—7 of Fig. 2;

Fig. 8 is a side view of the brush and its holder removed from the timer; and

Fig. 9 is a section taken on the line 9—9 of Fig. 8.

While the timer disclosed herein is especially adapted for use on Ford engines, it should be understood that this example is for illustrative purpose merely, and that my invention is intended for timers in general, that is, for use on any internal combustion engine.

The shell or casing designated generally by 11, may be carried on any support in a position concentric with respect to a timer shaft 12 and with capacity to oscillate about such shaft. In the present instance, the shell may be oscillated by operation of an eye bracket 13 to which the usual spark advancing and retarding rod, not shown, is connected. This shell houses a rotating contact or brush on the shaft 12 and carries the insulating block and cover which will be presently described.

The rotating contact or brush 14 is carried

by a suitable holder 15 fixed to the timer shaft 12. The brush, preferably in the form of a block having a rectangular contact face 16, is slidably supported in a recess 17 in 5 the holder, an expansion spring 18 serving to constantly urge the brush forwardly into contact with the track which will be presently described, and a stop screw 19 serving to prevent ejection of the brush when said 10 track is removed. Viewing Fig. 4, it will be observed that the initial contact edge 21 of the brush is disposed in a radial plane with respect to the timer shaft. The face of the brush and the initial contact edge 21 are 15 designed to function in a particularly advantageous manner in connection with the track elements which will presently be described.

The contacts with which the brush makes 20 contact are carried by an insulating block designated generally by 22. This block has an annular shoulder 23 on its inner side, which seats on the outer edge of the shell 11. Said block carries on its inner side 24, a 25 series of segmental contact elements 25 and track elements 26 in alternating, circumferentially spaced relation. The inner faces of these elements are disposed in a common plane and form a track interrupted only by 30 the space between such elements. This space in each instance is of much less width than the face 16 of the brush so that the latter in moving over the track will be in continuous contact therewith. The track therefore, provides a continuous support for the 35 brush face, and inasmuch as the elements making up the track are metallic, an all-metal track is provided. A track of this kind will wear evenly throughout its length; 40 and it follows that the contacts 25 being component parts of the track, will wear evenly from end to end, and thus have greater longevity than the contacts in prior timer constructions, in which the revolving 45 contact does not move on a track, or in the event that it does, the track is not all-metal and uneven wear develops. It will be observed that the track elements are segmental in form and provide a relatively wide track 50 face; furthermore, that the initial contact edge 27 of each terminal contact 25 is disposed in a radial plane coincident with the plane of the edge 21 on the brush so that the latter will make simultaneous contact 55 from end to end with the terminal contact. This also prevents uneven wear and at the same time prevents arcing at the contact point and insures conduction of full capacity which is essential for the best ignition.

60 In the preferred form of my invention, the block 22 is cast from suitable insulated material and the segmental elements making up the track are set in the mold and thereby embedded in the casting. In order to 65 securely retain the segmental elements 26 in

the block, each is formed at its inner end with marginal shoulders or flanges 28. The contact elements are likewise formed so that when embedded, they will be securely held in position against displacement. The construction of the contact elements herein disclosed is particularly desirable as it permits manufacture at a comparatively low cost. In practice, I prefer to form these elements from a piece of brass rod. In the course of 70 manufacture, each piece of rod is upset at one end, providing a head 29, and this head will be finished to provide the desired segmental shape as shown. The shank 31 will be threaded at its end 32, which serves as the 75 binding post and the intermediate portion may be shaped to provide grooves 33 for reception of the insulating material. Such grooves may be either a continuation of the threads 32 or they may be independent thereof as in the present case, permitting the shank to be of larger diameter.

The conductor wires 34 may be connected to the binding posts 32 by any suitable means, and at present are equipped with connector plates 35 clamped to such posts by nuts 36 threaded thereon. Said wires emanate from one side of the insulation block, as shown plainly on Fig. 2, and pass through grooves 37 formed in the raised marginal 95 flange 38 on said block. These grooves serve to properly locate the wires and hold them in spaced relation.

The cover 39 seats on the flange 38 on the insulating block and fits the annular locating shoulder 41 thereon. This cover forms an effective housing for the conductor connections and closes the open side of the grooves 37, thus serving to prevent displacement of the conductor wires.

Means is now provided, preferably carried by the shell 11, for detachably holding it and the insulating block and the cover in operative relation. This means comprises spring snap fasteners on diametrically opposed sides of the shell, each having spring arms 42 and 43, the former of which is adapted to engage over the peripheral edge 44 of the insulating block and the latter over the edge 45 of the cover. Each pair 110 of spring arms may be formed from a single piece of spring material, and this may be riveted to the outside of the shell as shown. The raised edge 45 is notched at 40 for reception of the ends of the spring arms 42, so 115 that the latter may be unrestricted in its engagement with the edge 44.

In order to properly locate the contact-carrying block with respect to the shell, I have provided interfitting parts, shown on 125 Figs. 3 and 5, comprising a recess 46 in the forward edge of the shell adapted to receive a locating boss 47 on the block. In the use of this timer on different engines, it is sometimes desired to change the location of the 130

contact carrying block with respect to the shell, and in such event an additional recess 46 may be provided, making the timer adaptable to either one engine or the other.

- 5 In practice, the timer as a whole may be held in position by means of the usual spring element, not shown, which engages in the socket 46 in the cover.

From the foregoing, it will be seen that 10 the cover and contact-carrying block units may be removed either independently or together simply by withdrawing them against the pressure of the spring arms 42 and 43. Thus, these units may be quickly and conveniently removed without the use of tools 15 and without removing fastening elements of any kind. Removal of the cover gives access to the binding posts and connections which may be inspected or repaired as the 20 case may require, without removal of the contact-carrying block or the shell. For inspection of the contacts the block may be removed, and if necessary, the contact surfaces may be cleaned or refinished as described 25 above. In operation the all-metal track, so called by reason of the fact that the revolving contact has continuous bearing on the segmental metal track surfaces, is especially desirable, because it insures even wear, 30 longevity and a smooth running motor, and when necessary, its face may be easily cleaned or refinished.

It is believed that the foregoing conveys a clear understanding of the objects preferred above, and while I have illustrated but

a single working embodiment, it should be understood that changes might be made in details of construction without departing from the spirit and scope of the invention as expressed in the appended claims. 40

I claim:—

1. In a timer, in combination, a shell, a rotating brush within the shell, a contact-carrying block removably seated on the shell, a cover removably seated on the block and enclosing the contact lead wire connections, and a plurality of spring elements secured at diametrically spaced positions on the shell, each spring element having two spring fingers, one having yielding connection with 45 the contact-carrying block and the other having yielding connection with the cover for holding them in position and permitting quick detachment of the block and cover as a unit or of the cover independently of 50 the block. 55

2. In a timer having in combination a shell, a rotating brush within the shell, a contact-carrying block removably seated on the shell and a cover removably seated on the block serving to enclose the contact lead wire connections, a plurality of spring clips secured at circumferentially spaced points on the shell providing fingers some of which engage the contact-carrying block and the 60 others of which engage the cover whereby to permit quick detachment of the block and cover as a unit or of the cover independently of 65 the block. 65
